CONTROL DEVICE

Cecil S. Kelley, Forest Hills, Pa., assignor to The
Westinghouse Air Brake Company, Wilmerding,
Pa., a corporation of Pennsylvania

Application October 30, 1942, Serial No. 463,915

3 Claims. (Cl. 74—471)

1

This invention relates to control valve devices for governing flow of fluid under pressure and more particularly to the manually operative type.

In the patent of Roy R. Stevens, No. 2,383,278, August 21, 1945, there is disclosed an arrangement for selectively controlling the maneuvering gear of a reversible Diesel engine which is employed to propel a water craft. This maneuvering gear has a neutral position in which the engine is stopped, and is rotatable to one side of neutral position to a start position for causing the engine to be placed in operation in a direction to cause movement of the ship forwardly. Between this start position and the neutral position there is a full position to obtain full engine speed ahead, a slow position to cause operation of the engine at idling speed, and the maneuvering gear may be adjusted to any selected position between said full and slow positions to obtain different engine speeds. There is also a stop position for stopping the engine. The maneuvering gear is also rotatable to the opposite side of neutral position to reversely arranged start, full, slow, and stop positions for obtaining astern movement of the craft.

For positioning the maneuvering gear a fluid motor is provided which is operative by fluid pressure supplied to either one of two pipes while the other pipe is open to the atmosphere, the pipe supplied with fluid under pressure determining the side of neutral position to which the maneuvering gear will be operated, and the degree of fluid pressure provided in the selected pipe determining the position to which the maneuvering gear is moved.

The principal object of the invention is the provision of a multi-position operator's control device for selectively controlling pressure of fluid in two pipes to govern operation of a motor such as above described and embodying novel arrangements for defining different positions thereof and for automatically preventing said device inadvertently remaining in certain of said positions.

Other objects and advantages will be apparent from the following more detailed description of the invention.

In the accompanying drawings: Fig. 1 is an elevational view of one end of the improved control device; Fig. 2 is a sectional view taken generally on the line 2—2 in Fig. 1 but with certain parts broken away to more clearly show certain interior construction of the device; Figs. 3 to 6 are sectional views taken substantially on the lines 3—3, 4—4, 5—5, and 6—6, respectively, in Fig. 2; and

2

Fig. 7 is a sectional view taken on the line 7—7 in Fig. 6.

Description

As shown in the drawings, the control valve device comprises an irregular ring-shaped combined mounting and pipe bracket 1 having suitably located holes 2 to receive securing bolts for mounting the device in a desired position. A base member 3 is secured by cap screws 4 to the upper face of the bracket 1 and a casing section 5 is secured by cap screws 6 to the lower face of the base member 3 within the bracket 1.

The base member 3 has two vertically extending parallel arranged end walls 7 and 8 connected together adjacent their base by a raised portion 9. At one side of the raised portion 9 and between the base member 2 and the top of end walls 7 and 8, said walls are connected together by the strengthening rib 10.

The raised portion 9 has substantially midway between the end walls 7 and 8 a chamber 11 and an inner wall 12 separating said chamber from a chamber 13 provided above a flexible diaphragm 14. The two chambers 11 and 13 are in communication with each other through a stabilizing choke 15.

The diaphragm 14 is clamped around its edge between the lower face of the base member 3 and the adjacent end of the casing section 5. An oppositely arranged and axially aligned flexible diaphragm 16 is clamped around its edge between the opposite end of casing section 5 and a cover 17. A chamber 18 is formed between the diaphragm 16 and cover 17 and is in constant communication with the atmosphere through an opening provided in an insect excluder 19. The adjacent faces of the two diaphragms 14 and 16 are open to chambers 20 and 21, respectively, which are in permanent communication with each other through a passage 22 provided in an annular rib 23 projecting inwardly from the casing section 5 above the diaphragm 16. In use, chamber 20 is constantly supplied with fluid under pressure from any suitable source by way of

a supply pipe 27 connected to the bracket 1 and opening to a passage 28 in the base member 3 which passage in turn opens to a passage 29 in the casing section 5, the passage 29 leading to chamber 20.

The rib 23 supports in chamber 20 one end of a control spring 38 the opposite end of which bears against an annular spring seat 39. The seat 39 is mounted on a stem 27 and urged by spring 38 against a shoulder 48 on said stem. The spring

38 is fully expanded with the parts of the device in the position shown and is operative to oppose downward movement of the stem 27 and thereby of diaphragms 14 and 16 from this position, as will be hereinafter described.

The central portion of diaphragm 14 is clamped between two followers 24 and 25, the follower 25 engaging an annular collar 26 provided on stem 27, which stem extends through the chamber 20 and said followers and diaphragm into chamber 13. A nut 28 disposed in chamber 13 has screw-threaded engagement with the wall of a bore 29 provided in the end of stem 27 and is tightened against the follower 24.

The rib 23 has a bore lined with a wear bushing 30 arranged in axial alignment with the two diaphragms 14 and 16, and the stem 27 extends through this bushing and centrally through the diaphragm 16 into chamber 18. Above the rib 23 the stem 27 is reduced in section to provide a shoulder 32, and a wear sleeve 31 is mounted on this reduced portion of the stem with one end in engagement with said shoulder. The sleeve 31 extends through bushing 30 in sliding contact therewith and its opposite end contacts a follower 33 which is disposed in chamber 21 in contact with the upper side of the diaphragm 16. The stem 27 extends through follower 33 and a follower 34 mounted against the opposite face of the diaphragm 16, and a nut 35 provided on the end of stem 27 in chamber 18 is tightened against the follower 34 clamping same centrally to one side of the diaphragm 16 and thereby securing the follower 33 against the opposite side of the diaphragm.

An adjusting screw 36 having a screw-threaded connection with cover 17 extends through said cover into chamber 18 in alignment with nut 35 for engagement thereby. A lock nut 37 is provided on screw 36 for engagement with the exterior of the cover 17 to lock said screw in an adjusted position.

The nut 28 above diaphragm 14 has an upwardly extending sleeve-like projection 40 the end of which is mounted to slide in one end of a sleeve 41. This end of sleeve 41 is secured in a bore through wall 12 and the sleeve extends through chamber 11 and the opposite wall thereof in the raised portion 9 of the base member 1 to a point above said raised portion between the end walls 7 and 8.

The bore 29 in the diaphragm connecting stem 27 is in permanent communication through a smaller bore 42 and one or more radial ports 43 with chamber 20 and contains a fluid pressure supply valve 44 having a fluted stem 45 extending through an axial bore provided in nut 28 into the projection 40 thereof wherein it contacts a fluid pressure release valve 46. The nut 28 is provided with a seat for engagement by the valve 44 and a spring 49 extending through bores 29 and 42 acts on said valve for urging same into contact with said seat.

A plunger 50 is slidably mounted in sleeve 41 above the release valve 46 and is provided with an annular groove 51 in which there is disposed a sealing ring 52 contacting the bottom of said groove and the wall of said sleeve for preventing leakage of fluid under pressure from a chamber 53 below the plunger to an annular chamber 54 above the plunger. The chamber 53 is in permanent communication with the interior of the sleeve projection 40 of nut 28 and through one or more radial ports 55 in sleeve 41 with chamber 11. The chamber 54 is constantly open

to the atmosphere through one or more radial ports 56 provided in sleeve 41 above the plunger 50.

The plunger 50 has a portion 57 of reduced section depending therefrom into chamber 53 and provided with an axial bore opening through a valve seat on its lower end which is provided for engagement by the release valve 46. The release valve 46 has a fluted stem 58 extending through this bore into a bore 59 of larger diameter in which there is slidably mounted a spring seat 60 having one or more openings 61 adjacent its peripheral edge connecting the spaces at opposite sides of said seat. The plunger 50 also has an upwardly projecting portion 62 of reduced section extending through chamber 54 and in sliding engagement with an inturned collar 63 provided at the upper end of sleeve 41. The bore 59 extends to a point above collar 63 where it joins a screw-threaded bore 64. Just below the end of the screw-threaded bore 64, the portion 62 of plunger 50 has two oppositely arranged radial bores 65 in which are disposed pins 66 extending from opposite ends of a cylindrical spring seat 67 which is of slightly smaller diameter than bores 65 so that said seat may be inserted into bore 59 through either of the bores 65. A coil spring 68 is disposed in bore 59 under pressure and acts at one end on the spring seat 67 and at the opposite end on the spring seat 60, this spring biasing the release valve 46 to its open position shown and moving the spring seat 67 upwardly until the pins 66 engage the uppermost portions of the bores 65 in which position the spring seat 67 is held against longitudinal movement and thus secured within the bore 59.

An operating screw 70 is threaded into bore 64 and on its outer end is provided with a head 71. A lock nut 72 on screw 70 is arranged to engage the end of the extended portion 62 of plunger 50 for securing the screw 70 in an adjusted position. A coil bias spring 73 under pressure encircles the portion of sleeve 41 extending above the raised portion 9 of the base member 1 and is supported at one end on said member while its opposite end bears against a ring-shaped seat 74 secured on the portion 62 of plunger 50 by suitable interlocking means 75.

The raised portion 9 of the base member 1 contains two like selector valve devices 82 and 83 arranged one at each of the opposite sides of chamber 11 and thus between said chamber and the end walls 7 and 8, respectively.

The selector valve device 82 comprises two oppositely seating axially aligned poppet valves 85 and 86 which are arranged to move in a direction at right angles to the axis of sleeve 41. The valve 85, which is a fluid pressure supply valve, is contained in a cavity 87 which is open to chamber 11, and said valve has a fluted stem extending through a wall 88 into a chamber 89 which is open to a pipe 90. The valve 86, which is a release valve, is contained in a chamber 91 which is open through a passage 92 to the atmosphere. The valve 86 has a fluted stem extending through a wall 93 into chamber 89 wherein it engages the stem of the supply valve 85. The stems connecting the two valves provide for seating of one valve when the other is unseated.

A cap nut 94 closes an opening to cavity 87 and has a bore containing a coil spring 95 which bears against the supply valve 85 for seating same and at the same time unseating the release valve 86. A cap nut 96 closes an opening to the release valve chamber 91 and is provided with a through bore in axial alignment with said valve and in

which there is slidably mounted an operating sleeve 97. The sleeve 97 is closed at its outer end but has a bore open at its inner end and in this bore is slidably mounted a plunger 98 which bears against the release valve 86 and behind this plunger is a spring 99 under pressure and acting on said plunger. The plunger 98 has a stem 100 extending through spring 99 and in the inner end of said stem is a diametrical elongated slot through which extends a pin 101 secured at opposite ends in sleeve 97. With the release valve 86 unseated by spring 95 the pressure of spring 99 is removed from said valve by engagement of pin 101 with one side of the slot in the plunger stem 100. Upon inward movement of sleeve 97 it acts through spring 99 on plunger 98 to seat the valve 86 and unseat valve 85. The spring 99 then provides for further inward movement of the plunger 97 relative to the release valve 86, by means which will be hereinafter described.

The selector valve device 83 is identical in structure to the device 82 and therefore will be described only briefly. The selector valve device 83 comprises a supply valve 105 contained in a cavity 106 which is open to chamber 11 and is operative to control communication between said cavity and a chamber 107 which is open to a control pipe 108. The valve device further comprises an oppositely seating release valve 109 contained in a chamber 110 which is open to atmosphere through a port 111. The release valve 109 is arranged to control communication between chamber 110 and chamber 107. A spring 112 in chamber 106 acts on the supply valve 105 to seat same and at the same time unseat the release valve 109, while a plunger 113 is arranged to be operated by a spring 114 upon inward movement of an operating sleeve 115 to seat the release valve 109 and open the supply valve 105.

It will now be seen that while both of the selector valve devices are of identical structure, the selector valve device 82 is provided for controlling communication between pipe 90, and chamber 11 and atmosphere, while the selector valve device 83 is provided to control communication between pipe 108, and chamber 11 and atmosphere.

Directly above the screw 10 connected with plunger 50 there is an operating shaft 120 extending at right angles to the axis of said plunger between the end walls 7 and 8. This shaft has at one end an enlarged portion 121 which is journaled in a bushing 122 secured in the end wall 7 while the opposite end of the plunger extends through a bushing 123 secured in the wall 8. Slidably mounted on shaft 120 between the end walls 7 and 8 are cams 124 and 125 disposed directly over the selector valve devices 82 and 83 respectively, and a cam 126 disposed directly over the plunger operating screw 10. Between the cams 124 and 126 is a disk-like quadrant 127, while between the cams 125 and 126 is a spacer sleeve 128.

The operating shaft 120 is provided with a slot extending substantially from wall 7 to wall 8 and in this slot is a key 129. The cams 124, 125, and 126 and the quadrant 127 are properly grooved to receive the key 129 for securing said cams and quadrant in desired relative positions on the shaft for rotation therewith. In assembling, the shaft 120 is threaded through the bushing 122 and then serially through the several cams, the quadrant, the spacer sleeve and finally through the bushing 123 into which a bearing sleeve 130 is inserted over the end of the shaft.

The combined lengths of the shaft bearings in the several cams, in the quadrant and in the spacer sleeve is substantially the same as the distance between the bearing bushings 122 and 123 in order to hold the cams and quadrants in definite positions between the walls 7 and 8.

A hand operated lever or handle 131 is provided for turning the shaft 120 and thereby the several cams and quadrant mounted thereon. By way of example the lever 131 may have at either side of a "neutral" position, zones of movement such as indicated in Fig. 1 by the legends "Ahead" and "Astern," and in each zone there may be a plurality of different positions such as are also indicated in Fig. 1 by legends.

This lever 131 comprises an operating member 132 slidably mounted on a reduced portion of the shaft 120, which projects beyond the wall 8, into contact with a shoulder 133 on the shaft and with the adjacent end of sleeve 130. A key 134 secures the shaft 120 to the lever 131 for rotation therewith. A nut 135 on the end of the shaft secures the operating member 132 against the shoulder 133 and thereby against the adjacent end of sleeve 130 which acts against the cam member 125. Since the cam 124 is in contact with the enlarged end portion 121 of the shaft 120, said shaft is thus secured against longitudinal movement in the walls 7 and 8.

The hand operated lever 131 further comprises a spindle 136 one end of which is rigidly connected by screw threads and a rivet 137 to the operating member 132. A locking member 138 is slidably mounted on the spindle 136 to a position adjacent the operating member 132 and beyond this locking member is a hand grip portion 139 screw-threaded to the spindle 136 as at 140. The inner end of the hand grip portion 139 has a recess in which there is disposed a coil spring 141 which is under pressure and bears against the locking member 138 for urging same in the direction of the operating shaft 120. A recess 142 is provided in the opposite end of the hand grip portion 139 for receiving a nut 143 which is secured by screw-threads to the outer end of spindle 136. The outer end of recess 142 is closed by a cap 144 secured in the end of the hand grip portion 139 by a rivet 145. It will be seen that due to the screw-threaded connection between the hand grip 139 and spindle 136 said grip is capable of rotation relative to the spindle, and upon rotation in one direction will move longitudinally of the spindle toward the locking member 138 while upon rotation in the opposite direction said grip will move away from said locking portion.

Projecting from wall 8 in the direction of stem 136 is an arcuate rib 146 having formed around its outer surface an arcuate V-shaped rail 147 arranged concentric to the operating shaft 120. The operating member 138 on spindle 136 has a projection provided with an arcuate groove into which the rail 147 fits, the rail being of such length as to remain in said groove throughout the full range of movement of the lever 131. When the grip 139 is turned on the spindle 136 against the locking member 138, said member is forced against the rail 147 to thereby secure the hand operated lever 131 against movement. In order to move the lever 131, the grip 139 is turned out of contact with the locking member 138 whereupon the force between said member and the rail 147 is reduced to the small amount provided by spring 141 which does not interfere with free movement of said lever, but which main-

tains the parts constantly in cooperative relation and avoids chattering between said parts.

A fulcrum bar 148 arranged parallel to the operating shaft 120 is disposed at one side thereof substantially opposite the rib 10 and has its opposite ends supported in suitable bores through the end walls 7 and 8. Rockably mounted on this bar are two levers 149 and 150 aligned with the peripheries of cams 124 and 125, respectively, a quadrant arm 151 aligned with the periphery of quadrant 127, and an arm 152 aligned with the periphery of cam 126, and between the lever 150 and arm 152 is a spacer sleeve 123 which is secured to the bar 148 by a key 154. The combined length of the bearing portions of the two levers 149 and 150 of the two arms 151 and 152, and of the sleeve 153 is substantially the same as the distance between the walls 7 and 8 carrying the ends of the fulcrum bar 148 so as to thereby maintain the different levers and arms in cooperative relation with the respective cams or quadrant on the operating shaft 120, and the key 154 cooperates with said bar to hold these parts properly assembled between the ends walls 7 and 8.

The quadrant arm 151 extends from the fulcrum bar 148 underneath and beyond the center of the quadrant 127 and in its free end is provided with a recess 160 open to the lower face of the arm. A pin 161 having its lower end supported in a recess provided in the raised portion 9 of the base member 1 extends through the recess 161 and a bore opening through said arm into the bottom of said recess. A coil spring 162 under pressure and encircling the pin 161 is supported at one end on a collar 163 fixed on said pin while the opposite end engages the arm 151 within the recess 161. Substantially below the quadrant 127 the arm 151 has a raised portion 164 which is urged against the peripheral surface of quadrant 127 by the spring 162.

The quadrant 127 is provided in its peripheral surface with a recess 165 to receive the raised portion 164 of arm 151 when the operating lever 131 is in "neutral" position shown for defining said position. At one side of recess 165 the quadrant has a recess 166 for receiving the raised portion 164 of arm 151 when the operating lever 131 is in the "stop" position in the "astern" zone. Another recess 167 is provided in the quadrant to receive the raised portion 164 of lever 151 for defining the "slow" position in the "astern" zone. Still another recess 168 is provided in the quadrant for receiving the raised portion 164 of arm 151 for defining "full" position of the operating lever 131 in the "astern" zone. Movement of the lever 131 past this "full" position to the adjacent "start" position is provided for by the slope 169 of one side of the recess 168 and it will be noted that the force of spring 162 applied through the raised portion 164 on arm 151 to this slope will tend to return the operating lever from said "start" position to said "full" position.

At the opposite side of recess 165 the quadrant 127 is provided with recesses 170, 171, and 172 for defining the "stop," "slow," and "full" positions, respectively of the operating lever in the "ahead" zone, one side of recess 172 constituting a slope 173 to function like the slope 169, above described.

It will be apparent that cooperation of the raised portion 164 on the quadrant arm 151 with the different recesses in the quadrant 127 not only act to define the different positions of the operating lever 131 but also to oppose movement 75

of said lever from one position to another and thus tend to prevent accidental shifting of said lever.

The lever 149 has an upwardly extending arm 5 provided on its end with a nose 175 disposed to contact the peripheral surface of cam 124. This lever also has a downwardly extending arm 176 in the lower end of which is screw-threaded an adjusting screw 177 arranged to engage the operating sleeve 97 of the selector valve device 82. A lock nut 178 is provided on the screw 177 for engagement with arm 176 to secure the screw 177 in an adjusted position.

Directly above the selector valve device 82 is a pin 180 having one end supported in the arm 176 adjacent the adjusting screw 177. This pin is 15 slidably mounted in a bore provided through a rib 181 connecting the raised portion 9 of the base member to the end wall 7. A spring 182 20 encircling the pin 180 bears at one end against the rib 181 and at the opposite end against a collar 183 provided on the pin adjacent the lever arm 176. This spring is under pressure and therefore effective to hold the nose portion 175 25 of lever 149 in constant contact with the peripheral surface of cam 124.

The peripheral surface of cam 124 has a portion 184 formed at a radius to permit the lever 149 to occupy the position shown in Fig. 4 in 30 which the supply valve 85 of the selector valve device 82 is seated and the release valve 86 is open. The surface of cam 124 also has a portion 185 formed at a greater radius for displacing the lever 149 in a clockwise direction as viewed in 35 Fig. 4 for seating the release valve 86 and opening the supply valve 85. These two portions 184 and 185 of the peripheral surface of cam 124 are joined by a connecting portion 186 which is so located that upon clockwise movement of the 40 operating lever 131, as viewed in Fig. 4, or open movement of said lever into the "ahead" zone, the release valve 86 of the selector valve device 82 will be closed and the supply valve 85 opened by cam 124 in a position of said lever intermediate 45 the "neutral" and "stop" positions in said zone and then be maintained in this condition in all positions of said lever between such intermediate position and the "start" position at the opposite end of said zone. When the lever 131 is moved 50 to "neutral," the portion 184 of the surface of cam 124 will be moved under the nose 175 of lever 149 to permit seating of the supply valve 85 and opening of the release valve 86 just before obtaining "neutral" position and this condition 55 of said valves will then be maintained in all positions of the operating lever 131 at the opposite side of "neutral" position.

The lever 150 has one arm provided with a nose portion 190 engaging the peripheral surface of cam 125 and another arm 191 provided in its end with an adjusting screw 192 disposed to contact plunger 195 of the selector valve device 83, a lock nut 193 being provided on the screw 192 for engagement with said lever to secure said screw in an adjusted position. One end of a pin 194 is disposed in a recess in the lever arm 191 while its other end is slidably mounted in a suitable bore provided through a rib 195 connecting the raised portion 9 of the base member 2 with the side wall 8. A coil spring 196 mounted on pin 194 bears at one end against the rib 195 and at its opposite end against a collar 197 provided on said pin. This spring is under pressure and therefore 70 effective to hold the nose portion 190 of lever

191 in constant contact with the peripheral surface of cam 124.

The peripheral surface of cam 125 has portions 197 and 198 formed at different radii and connected by an inclined portion 199, these portions corresponding to like portions 184, 185 and 186 on the cam 124. The portion 199 of cam 125 is so located as to operate lever 150 for seating the release valve 109 and opening the supply valve 105 in the selector valve device 83 when the operating lever 131, upon counterclockwise movement as viewed in Fig. 5, or upon movement into the "astern" zone, passes through a position intermediate the "neutral" position and the "stop." The cam 125 is then adapted to maintain these valves in this condition in all positions of the operating lever 131 beyond this intermediate position in the "astern" zone and to provide for closing of the supply valve 105 and opening of the release valve 109 in all positions of said lever to the right of this intermediate position and in the "ahead" zone.

It will be noted that the two selector cams 124 and 125 are of identical structure but that one is mounted on the operating shaft 121 in turned over end to end relation with respect to the other. Each is provided with two key ways, as shown in Figs. 4 and 5, one key way for cooperation with key 129 to provide cam 124 and the other key way for cooperation with said key to provide the cam 125.

From the above description it will now be seen that with the operating lever 131 in "neutral" position, as shown in the drawings, the supply valves will be closed and the release valves open in both of the selector valve devices 82 and 83. When the operating lever 131 is turned out of "neutral" position into the "ahead" zone, the supply valve 105 will remain seated and release valve 109 unseated in the selector valve device 83, while in the selector valve device 82 the supply valve 85 will be opened and the release valve 86 closed in a position of the lever intermediate the "neutral" and "stop" positions, and this condition of these valves will then be maintained in all positions of the operating lever to the left (Fig. 1) of the intermediate position in the "ahead" zone. On the other hand when the operating lever 131 is turned from "neutral" position into the "astern" zone, the supply valve 85 will remain seated and the release valve 86 open in the selector valve device 82, while in the selector valve device 83 the release valve 109 will be closed and the supply valve 105 opened, and this condition of these valves will be maintained in all positions of the operating lever to the right (Fig. 1) of the intermediate position in the "astern" zone.

The arm 152 which is pivoted on the fulcrum bar 148 has its free end disposed between the peripheral surface of cam 126 and the head 71 of the adjusting screw 70 in the upper end of plunger 50, said free end being provided on one side with a rounded surface 200 having sliding contact with the screw head 71. In the opposite side of the free end of arm 152 is a recess formed between two jaws 201 and in which is disposed a roller 202 mounted to roll on a pin 203 carried by said jaws. The roller 202 is thus aligned for contact with the peripheral surface of cam 126 and it is constantly maintained in contact therewith by the pressure of spring 73 applied through seat 74 to the extension 72 of plunger 50 and thus through the surface 200 on arm 152 to the roller 202.

In the peripheral surface of cam 126 is a recess 204 arranged to receive the roller 202 with the operating lever 131 in its "neutral" position. The screw 70 in the extension 72 of plunger 50 is so adjusted that with the lever 131 in "neutral" position and with the diaphragms 14 and 16 in their normal positions and with the supply valve 44 seated as shown in Fig. 3, the release valve seat on the depending portion 57 of the plunger 50 will be spaced from the release valve 46 a chosen distance due to the action of spring 68 on the stem 58 of said valve which maintains same in constant contact with the stem 45 of the supply valve 44.

15 At one side of the recess 204 the cam 126 is provided with a surface 205 for contacting the roller 202 while at the opposite side of the recess is an identical surface 206 for contacting said roller, these two surfaces being arranged reversely so that the surface 205 will displace the roller 202 and thereby the plunger 50 from normal position shown in Fig. 3 in a downwardly direction upon movement of the operating lever 131 from "neutral" position into the "ahead" zone, while the surface 206 is provided to accomplish the same result upon movement of lever 131 in the opposite direction from "neutral" position into the "astern" zone.

Referring particularly to surface 205. When 30 the control lever 131 is turned into the "ahead" zone, this surface is arranged to move the depending portion 57 of the plunger 50 into engagement with the release valve 46 and to then 35 actuate said valve to open the supply valve 44 to a certain extent by the time the operating handle attains the "stop" position. Further movement of the operating lever 131 from "stop" position to "full" position in the "ahead" zone will then provide gradually an increased 40 placement of the plunger 50 in a downwardly direction. Continued movement of the operating lever from "full" to "start" position in the "ahead" zone will then provide still further downward movement of the plunger 50 and preferably of a 45 greater degree for the extent of lever movement than obtained between the "slow" and "full" positions for corresponding movement of the operating lever. The end of surface 205 opposite recess 204 joins an abrupt rise 207 formed substantially at the radius of roller 202 and which is provided for contact with said roller in the "start" position of the operating lever 131 for defining such position and preventing movement of said lever past same.

55 The portion of surface 205 engaged by roller 202 between the "full" and "start" positions is of such slope that the pressure of spring 73 applied through the roller 202 to said surface tends to return the lever 131 from the "start" position to 60 the "full" position. The purpose of this tendency is to automatically return lever 131 from "start" position to "full" position upon removal of manual force from said lever and this may be obtained by the sole action of either of spring 73 65 as just described or of spring 162 applied through the raised portion 164 of the quadrant arm 151 when in contact with surface 173 on the quadrant member 124, as above described, or preferably by the combined action of both springs.

70 From the above description it will now be seen that plunger 50 will occupy its most elevated position with respect to cam 126 when the operating lever 131 is in its "neutral" position and due to action of cam surface 205 upon movement of 75 said lever out of said position into the "ahead"

zone, said plunger will be displaced downwardly from its normal position to an extent dependent upon the position of the operating lever away from "neutral" position, the maximum displacement of said plunger being attained in the "start" position.

Upon movement of lever 131 from "neutral" position into the "astern" zone the cam surface 266 and an abrupt rise 208 at the end of said surface opposite recess 204 is arranged to function identically to surface 205 and rise 207 upon movement of the operating lever 131 in the "ahead" zone as above described.

An inverted substantially U-shaped cover 210 extends between the end walls 7 and 8 with flanges 211 overlapping the outer surfaces of said walls and from the base member 3 at one side of the device to the base member at the opposite side and is secured at opposite ends to said base member by cap screws 212 thereby fully enclosing the cams, levers, springs, and all other parts of the device disposed between the two walls of the base portion.

Operation

In operation, let it be assumed that the supply pipe 77 is connected to any suitable source of fluid at a pressure such as eighty-five pounds per square inch as a result of which fluid at the same pressure will be effective in chamber 20 between the two diaphragms 14 and 16. Due to the fact that the opposing areas of diaphragms 14 and 16 are the same, the pressure of fluid in chamber 20 acting on one diaphragm will equal and balance that acting on the other diaphragm. Also let it be assumed that the operating lever 131 is in "neutral" position and that the adjusting screw 70 has been adjusted to allow, in said position, unseating of the release valve 46 with the control spring 38 fully expanded. As a result, chamber 11 and thereby cavities 87 and 106 containing the supply valves 85 and 105 of the selector valve devices 82 and 83 will be open to atmosphere past the release valve 46, spring seat 60, chamber 54 surrounding the extension 62 of plunger 52 and thence through port 56. With the operating lever 131 in its "neutral" position the supply valves 85 and 105 in both of the selector valve devices 82 and 83 will be closed and the release valves 86 and 109 will be open so that both control pipes 90 and 108 will be open to the atmosphere past said release valves and thence through ports 92 and 111, respectively.

Now let it be assumed that the operator moves the operating lever 131 to "stop" position in the "ahead" zone. This movement actuates the cam 124 and thereby the lever 149 to seat the release valve 86 and open the supply valve 85 in the selector valve device 82 to thereby connect pipe 90 to chamber 11, while simultaneous operation of cam 125 allows the valves in the selector valve device 83 to remain in the position shown in Figs. 5 and 6 in order to maintain the control pipe 108 open to the atmosphere with the operating lever in "ahead" zone.

When the lever 131 is moved to the "stop" position just described the cam 126 is operated to move plunger 50 into seating engagement with the release valve 46 and to then move said valve to unseat the supply valve 44 to a slight extent. Fluid under pressure supplied to chamber 20 between the two diaphragms then flows past the supply valve 44 to chamber 11 and thence past the supply valve 85 in the selector valve device 82 to the control pipe 90 for increasing the pres-

sure therein above atmospheric pressure. At the same time as fluid is thus supplied through chamber 11 to pipe 90 it also flows from said chamber through the stabilizing choke 15 to chamber 13 above the diaphragm 14 wherein the pressure increases substantially with the increase in pipe 90. When the pressure thus obtained in chamber 13 and acting on the upper face of diaphragm 14 becomes increased to a sufficient degree to overcome spring 38, the diaphragms 14 and 16 are deflected downwardly relative to the supply valve 44 and finally moves nut 28 into engagement with said valve for preventing further flow of fluid under pressure to chambers 11 and 13 and pipe 90. The supply valve 44 is thus closed in a position of the diaphragms 14 and 16 and in a pressure condition of spring 38 determined by the extent of downward movement of said valve by the cam 126 and therefore by the position of lever 131, and it may be assumed that this occurs when the pressure in chambers 11, 13, and pipe 90 is increased to a degree such as ten pounds with the operating lever in the "stop" position.

If the lever is now moved from "stop" position to "slow" position in the "ahead" zone the supply valve 44 is displaced downwardly further and out of seating contact with nut 28 following which fluid will again flow from diaphragm chamber 20 to chamber 11 and thence to pipe 90 and chamber 13. The consequent increase in pressure in chamber 13 will then move the diaphragm 14 downwardly to again cut-off the supply of fluid past the valve 44 when the pressure in pipe 90 is increased to a degree corresponding to the new position of the supply valve 44 as determined by the control lever 131 in the "slow" position.

If the operating lever 131 is now moved from the "slow" position to "full" position in the "ahead" zone a corresponding further downward movement of the supply valve 44 away from the end of nut 28 will occur to allow further flow of fluid under pressure from chamber 20 to chamber 11 and thence to pipe 90 and chamber 13 at the upper side of diaphragm 14 and as a result the diaphragm 14 will be deflected downwardly further against spring 38 and again cause seating of the nut 28 against the supply valve 44 when the pressure in said pipe is increased to the degree called for by the position of the operating lever. The pressure attained in pipe 90 in "slow" position of lever 131 may for instance be twenty pounds per square inch while that attained in "full" position may be of a degree such as sixty pounds. If instead of being moved to the "full" position the lever 131 is moved to a position intermediate the "slow" and "full" positions, in the "ahead" zone, the corresponding downward movement of the supply valve 44 will result in a corresponding less degree of pressure being attained in the control pipe 90. Thus the pressure attained in pipe 90 may, by proper positioning of the control lever 131 between the "slow" and "full" positions in the "ahead" zone be limited to any desired intermediate degree.

If the operating lever is now moved from "full" position to "start" position the supply valve 44 will again be unseated for increasing the pressure of fluid in pipe 90 which will cause further downward movement of the diaphragms. However, upon a slight downward movement of the diaphragms in response to this increase in pressure in chamber 13 the nut 35 on the end of the diaphragm connecting stem 21 will preferably engage the adjusting screw 36 and limit such

downward movement to a position in which the supply valve 44 will be maintained open in order that the pressure in pipe 90 may increase to the maximum degree effective in chamber 20 between the diaphragms, or to a pressure such as eighty-five pounds.

Upon removal of manual force on lever 131 in the "start" position, said lever will automatically be returned to "full" position by forces hereinbefore described and aided by the pressure of fluid in chamber 11 acting in the plunger 50. Since the pressure in chamber 13 will initially hold the diaphragms 14 and 16 against movement by spring 38 upon such movement of lever 131, spring 47 will hold the supply valve 46 seated and the depending portion 57 of plunger 50 will therefore be moved by spring 73 and the pressure of fluid in chamber 11 acting on said plunger away from the release valve 46 which at this time will be held against movement by spring 68. As a result, fluid under pressure will flow from pipe 90 and chambers 11 and chamber 13 past the release valve 46 to the atmosphere. When the pressure of fluid in chamber 13 above diaphragm 14 is thus reduced sufficiently, the spring 38 will move the diaphragms 14 and 16 in an upwardly direction and through the supply valve 44 move the release valve 46 into seating engagement with the depending portion 57 of plunger 50 at the time the pressure of fluid in chamber 13 and pipe 90 becomes reduced to the degree (sixty pounds) called for with the operating lever 131 in the "full" position.

If the operating lever 131 is now returned from "full" to "slow" position the consequent upward movement of plunger 50 by spring 73 will again unseat the release valve 46 as a result of which the pressure in pipe 90 and in chamber 13 above the diaphragm 14 will again reduce past the release valve 46 and as this reduction takes place the diaphragm spring 38 will move the diaphragms 14 and 16 upwardly to cause seating of the release valve 46 at the time the pressure of fluid in pipe 90 and chamber 13 becomes reduced to the degree (twenty pounds) corresponding to the "slow" position of the operating lever. If the operating lever is returned only part way from "full" position toward "slow" position the pressure in pipe 90 will be correspondingly reduced, as will be apparent. If the lever is now returned from "slow" position to "stop" position, the plunger 50 will again be moved away from the release valve 46 by spring 73 and the pressure of fluid in pipe 90 and chamber 13 above the diaphragm 14 will then reduce and the spring 38 will act through spring 47 to seat the release valve 46 when this pressure is reduced to the degree (ten pounds) determined by the position of the operating lever. Return of the operating lever 131 to "neutral" position will permit plunger 50 to move to a position in which the release valve 46 will remain open as shown in Fig. 3 and above described and also will effect operation of the selector valve device 82 to open pipe 90 to atmosphere.

On the other hand, if the operating lever 131 is moved from its "neutral" position into the "astern" zone, the selector valve device 82 will maintain pipe 90 open to the atmosphere while the selector valve device 83 will be operated to open pipe 108 to chamber 11, following which fluid will be supplied to said pipe at a pressure depending upon the position of the lever in the "astern" zone and corresponding to the pressure obtained in the different like positions of said

lever in the "ahead" zone. Thus if the handle is moved into the "astern" zone to "stop" position, a pressure such as ten pounds will be provided in the control pipe 108. A pressure such as twenty pounds will be provided in pipe 108 in the "slow" position, sixty pounds in the "full" position, any desired intermediate degree of pressure between the "slow" and "full" positions, and the maximum pressure of eighty-five pounds will be obtained in pipe 108 in the "start" position. The valve mechanism including the diaphragms 14, 16, supply valve 44, release valve 46, plunger 50, and cam 126, constituting what is commonly known as a self-lapping valve device, thus operates the same for each direction of movement of the operating handle 131 from "neutral" position, the direction of movement of said handle, however, determining which of the pipes 90 or 108 is supplied with fluid provided by said mechanism.

In order to positively secure the operating lever 131 against accidental movement out of "neutral" position I provide a latch 214 for securing the operating lever in "neutral" position. This latch is mounted between two jaws 215 projecting from the wall 8 and is pivotally carried by a pin 216 secured in the jaws. The member 132 of the operating lever 131 has an extended portion provided in its end with a recess 217 so arranged as to receive latch 214 in "neutral" position of the operating lever for thereby positively securing said lever against movement in either direction from "neutral" position.

The wall 8 back of the pivoted portion of lock 214 has a recess in which is slidably mounted a plunger 218 and which contains a spring 219 acting on said plunger urging same against the pivoted portion of the latch. The latch has two flat sides for engagement by the plunger 215, one for engagement with the latch when released from the operating lever 131 as shown in Fig. 2 and the other for engagement when the latch 214 is disposed in the recess 217 in said lever, engagement between the plunger 218 and either of the flat sides being arranged to hold the latch in either one position or the other and to oppose movement of the latch out of such position.

Summary

From the above description it will now be seen that I have provided a relatively simple and compact manually operative control valve which will accurately provide in either of two pipes a control pressure corresponding to any selected position of the manually operable handle or lever in order to obtain positive control or positioning of a device such as the maneuvering gear hereinbefore referred to.

Having now described my invention, what I claim as new and desire to secure by Letters Patent, is:

1. A control device comprising a rockable shaft, a quadrant arranged to turn with said shaft and having a plurality of spaced recesses arranged in an arc concentric with said shaft and corresponding in number and spacing to different positions of said shaft, means arranged to turn said shaft to its different positions, a detent member arranged to enter one of said recesses in each different position of said shaft for defining said position, spring means acting on said detent member urging said detent member against said quadrant, a cam operable with said shaft, a controlled member arranged to be controlled by said cam, pressure means urging said controlled member against said cam, the surface

of said cam, cooperating with said controlled member upon movement of said shaft beyond positions defined by the two end recesses in said quadrant, being arranged so that the pressure of said controlled member against said cam by said pressure means will urge said shaft, cam and quadrant to the position defined by interengagement of said detent member with the adjacent recess in said quadrant.

2. A control device comprising a rockable shaft, a quadrant arranged to turn with said shaft and having a plurality of spaced recesses included in an arc concentric with said shaft and corresponding in number and spacing to different positions of said shaft, means arranged to turn said shaft to its different positions, a detent member arranged to enter one of said recesses in each different position of said shaft for defining said position, spring means acting on said detent member urging said detent member against said quadrant, a cam operable with said shaft, a controlled member controlled by said cam, pressure means urging said controlled member against said cam, said cam being arranged to cooperate with said controlled member in positions of said shaft beyond the two end recesses in said arc to define the last named positions of said shaft.

3. A control device comprising a rockable shaft, a quadrant arranged to turn with said shaft and

having a plurality of spaced recesses arranged in an arc concentric with said shaft and corresponding in number and spacing to different positions of said shaft, means arranged to turn said shaft to its different positions, a detent member arranged to enter one of said recesses in each different position of said shaft for defining said position, spring means acting on said detent member urging said detent member against said quadrant, one side wall of each of the two end recesses in said arc being arranged so that in a position of said shaft beyond each of said end recesses the pressure of said detent member against the said side wall of the respective end recess will urge said shaft back to the position defined by the adjacent end recess, a cam operable with said shaft, a controlled member controlled by said cam, pressure means urging said controlled member against said cam, said cam comprising means arranged to cooperate with said controlled member in the said positions of said shaft beyond the said end recesses to define the last named positions of said shaft, and other means operable to render said pressure means effective on said controlled member, in cooperation with the pressure of said spring applied through said detent member to said quadrant to urge said shaft back to the position defined by the adjacent end recess.

CECIL S. KELLEY.
